United States Patent Office

Des. 189,035
Patented Oct. 18, 1960

189,035

TILE

Wallace Lanz, New York, N.Y., assignor to Minnesota and Ontario Paper Company, Minneapolis, Minn.

Filed Nov. 30, 1959, Ser. No. 58,498

Term of patent 14 years

(Cl. D18—2)

FIG. 1

I claim:

The ornamental design for a tile, as shown and described.
